UNITED STATES PATENT OFFICE.

FRANK MAWSON, OF PHILADELPHIA, PENNSYLVANIA, ASSIGNOR OF ONE-HALF TO JOHN R. MAWSON, OF SAME PLACE.

DESIGN FOR A SHIRT-WAIST FORMER.

SPECIFICATION forming part of Design No. 35,049, dated September 3, 1901.

Application filed August 7, 1901. Serial No. 71,272. Term of patent 3½ years.

To all whom it may concern:

Be it known that I, FRANK MAWSON, a citizen of the United States, residing at Philadelphia, in the county of Philadelphia and State of Pennsylvania, have invented and produced a new and original Design for Shirt-Waist Formers, of which the following is a specification, reference being had to the accompanying drawings, forming part hereof.

Figure 1 is a perspective view of a shirt-waist former having my design. Fig. 2 is a sectional view of the same.

The leading or material feature of my design consists of a shirt-waist former having the general form of a crescent.

In the drawings, *a* represents a vertical support or plate provided at its upper portion with the eyes or openings *b*. Projecting from opposite sides of the plate or support *a*

are curved arms or plates *c*, which are slightly convexed rearwardly in respect to said support, as shown in Fig. 2, and at their outer ends they connect with arms or wires *d*, which are inclined outwardly and then downwardly to the base of the support *a*.

Having described my invention, what I claim as new, and desire to secure by Letters Patent, is—

The design for a shirt-waist former as herein shown and described.

In testimony whereof I have hereunto signed my name in the presence of two subscribing witnesses.

FRANK MAWSON.

Witnesses:

W. J. JACKSON,
JAS. A. RICHMOND.
